UNITED STATES PATENT OFFICE.

HARVEY F. JACKSON, OF BROOKLYN, NEW YORK, ASSIGNOR, BY MESNE ASSIGNMENTS, TO CONWELL GRAPHIC COMPANY, INCORPORATED, OF NEW YORK, N. Y., A CORPORATION OF NEW YORK.

ADVERTISING DEVICE.

Application filed December 7, 1923. Serial No. 679,265.

This invention relates to advertising devices, and with regard to certain more specific features, to a combined picture or the like and support therefor, together with 5 a support, on the device, for an article of merchandise or the like.

Among the several objects of the invention may be noted the provision of a simple and inexpensive device for displaying a picture 10 or suitable legends or the like, together with an article of merchandise; and the provision of a strikingly attractive device of this type which can be made from a single blank and shipped flat. Other objects will be in part 15 obvious and in part pointed out hereinafter.

The invention accordingly comprises the features of construction, combinations of elements and arrangements of parts, which are exemplified in the description hereinafter in 20 connection with the accompanying drawings, and the scope of the application of which will be indicated in the following claims.

In the accompanying drawings, in which 25 are illustrated two of various possible embodiments of the invention,

Fig. 1 is a face view of the device shown flat;

Fig. 2 is a front elevation of the device in 30 display position;

Fig. 3 is a right side elevation of Fig. 2;

Fig. 4 is a bottom view of Fig. 2;

Fig. 5 is a view similar to Fig. 1, showing a modification;

Fig. 6 is a front elevation of the device of 35 Fig. 5, showing it in display position.

Fig. 7 is a right side elevation of Fig. 6; and

Fig. 8 is a bottom view of Fig. 6.

Similar reference characters indicate corresponding parts throughout the several views of the drawings.

Referring now more particularly to Figs. 1 to 4 of the accompanying drawings, there 45 is illustrated at 1 a device formed of a single sheet of suitable material such as patent coated solid manila. For a size such as $8\frac{1}{2} \times 18$ inches, a thickness of 25 points is suitable.

The device may take a variety of forms. 50 In Figs. 1 to 4, the middle portion or central

part 2 of the device carries a suitable legend or picture, and the same is true of the end portions 8, 15 and the intermediate portions or adjacent parts 13, 14. The central and 55 intermediate portions 2, 13, 14 are cut out in such a way as to provide a platform portion 25 which remains united to the display along the score line 27, but is otherwise cut away from the main body of the display. The 60 recesses 29, 31 are provided in the platform section 25, to engage the intermediate portions 14, 13 respectively when the device is bent into display position. The platform device is so shaped with respect to the intermediate portions 13, 14, that when the platform section 25 is bent rearwardly into display position, the lower left and right portions 33, 35 of the platform section rests upon the edges 37, 39 of the cut out portion 65 of the intermediate sections 14, 13 respectively. This forms a secure support for the platform portion and for the article or articles of merchandise (represented conventionally at 41) thereon. The recesses 29, 70 75 31 are at such an angle and depth and width that when the device is in display position, the walls 47, 49 of the intermediate sections 14, 13 enter the respective recesses 29, 31, and the front edge 51, 53 of respective recesses fit snugly against the adjacent (front) 80 surface of the intermediate section 14, 13, as indicated in Fig. 4. This renders the device 85 slightly and attractive in appearance, and ensures stability for the device as a whole and for the platform in particular.

The lower portions 33, 35 of the platform device extend out into the respective intermediate section 14, 13 (Fig. 1). When the device is in display position, this construction 90 serves to support the article of merchandise 41 in a position forwardly of the upper part of the central portion 2, and forwardly of the intermediate sections 14, 13, thereby giving to the article 41 a striking 95 prominence.

The side portions 8, 15 stand at the rear of and at an angle to the main portion 2.

In making the device shown in Fig. 1, only two operations are required, namely, 100 lithographing or the equivalent, and die-cutting. The lines 9, 10, 11 and 12 indicate

scoring, to facilitate bending of the device from the flat or shipping form shown in Fig. 1 to the display form shown in Figs. 2 to 4.

- 5 Part of the device rests upon the floor or show case or the like, in a plane in advance of the other parts of the base. This fact coupled with the fact that the device is of one piece, with scoring converging toward 10 the top to make the device stable, ensures the rigidity and stability necessary for display purposes when substantially thinner material is used than is ordinarily used for display devices of similar size.
- 15 In the preferred construction there are four score lines 9, 10, 11, 12 which divide the article into five parts, 8, 13, 2, 14, 15. The two outer score lines 9, 12 converge toward the top. The two inner score lines 10, 11 20 begin adjacent the upper end of the outer score lines 9, 12 and converge toward the bottom. The part 2 which is included between the inner score lines 10, 11 may bear a suitable design (not shown), such as the 25 picture of a person or article or a suitable legend, for example, and is inclined rearwardly when in display position. The platform section 25 is adapted to carry an article of merchandise such as 41. The parts 30 8, 15, which are on the outside of the outer score lines, 9, 12 are in approximately vertical position and substantially in alignment with each other when the device is set up for display. The parts 13, 14 which are on the 35 outside of the inner score lines 10, 11 form an angle with the center part 2 and the outer parts 8, 15 and form the connecting links between the outer parts 8, 15 and the center part 2.
- 40 It will be seen that no extraneous supports are required, and no gluing or expensive folding is required, either in manufacture or installation of the article.

By having the sides of the article disposed 45 to the rear of the central portion, the central portion appears to stand out from the rest and to present a striking appearance, and the article of merchandise 41 is displayed in a prominent position.

50 The device is stable without the end sections 8, 15. These end sections may be dispensed with, if desired.

In Figs. 5 to 8 is shown a modified form, 55 wherein the platform section 25 is of some-what different shape. This is done partly to accommodate the aperture in the central portion 2 of the contour of the article 41 (in this case a bottle) so as to form a convenient support for the upper portion of the bottle, indicated at 49 in Fig. 7. The rear end of the platform section 25 is shown as reaching the supporting surface, so as to provide additional mechanical strength for supporting the article, and adding to the 60 stability of the device as a whole.

In this form shown in Figs. 5 to 8 the cut-out part of the middle section 2 is of such a size that the article of merchandise may pass partly into it (Fig. 7) instead of resting wholly in front of the lateral edges 47, 70 49 as in Figs. 1 to 4.

It will be seen from the above, and from Figs. 5 to 8, that the flat section or platform portion 25 has a contour where cut from the central part or middle portion 2 adapted to leave a re-entrant outline in said central part 2, said outline being adapted to fit an article supported on said flat section along a contour line shaped substantially as, and representing the line of intersection between the plane of the central part 2 with the object 41 being supported. This presents an ideal optical effect and at the same time makes a stiff and stable structure, not easily tipped over and from which the device being displayed cannot be readily knocked off.

The articles of both types herein illustrated may be shipped flat, and may be readily folded into shape for use by comparatively unskilled labor.

From the above it will be seen that the several objects of the invention are attained and other advantageous results achieved.

As many modifications of the embodiments above illustrated might be made without departing from the spirit or scope of the present invention, it is intended that the above description and accompanying drawings and claims shall be interpreted as illustrative and not in a limiting sense.

I claim:

1. The advertising device comprising a one-piece body having a plurality of score lines extending from top to bottom of the device and dividing the article into a plurality of parts, said score lines being formed so as to form a central part inclined rearwardly when in display position with angularly arranged adjacent parts; a supporting section cut from said central part and the adjacent parts, adapted to fold rearwardly on the central part and being of such length as to reach to and rest on the surface which supports said adjacent parts; notches in said flat section adapted to engage the adjacent parts at the openings left where the portions of the flat section were cut therefrom, said flat section having a re-entrant contour where cut from the central part adapted to leave an outline in the central part adapted to fit an article supported on said flat section along a contour line shaped as, and representing the line of intersection between the plane of the central part with the object being supported.

2. An advertising device comprising a central part and adjacent parts hinged thereto in a manner such as to cause the central part to be inclined rearwardly when in display position; a section cut from said central

part and said adjacent parts, adapted to fold rearwardly on the central part; and notches in said flat section adapted to directly engage the said adjacent parts at the 5 openings left where the portions of the flat section were cut therefrom, said last-named section being of such length as to reach to

and rest on the surface which supports said adjacent part, in order to increase stability.

In testimony whereof, I have signed my 10 name to this specification this 1st day of December, 1923.

HARVEY F. JACKSON.
